UNITED STATES PATENT OFFICE.

EDWIN J. McCORMICK, OF SYRACUSE, NEW YORK, ASSIGNOR TO THE
McCORMICK MANUFACTURING COMPANY, OF NEW YORK, N. Y.

DESIGN FOR A SLEEVE FOR EXPANSION-FASTENERS.

SPECIFICATION forming part of Design No. 32,445, dated April 3, 1900.

Application filed March 31, 1898. Serial No. 675,994. Term of patent 14 years.

To all whom it may concern:

Be it known that I, EDWIN J. McCORMICK, of Syracuse, in the county of Onondaga, in the State of New York, have invented and produced a new and original Design for Sleeves for Expansion-Fasteners, of which the following is a specification, reference being had to the accompanying drawings, forming a part thereof.

- 10 Figure 1 represents a side or face view of a sleeve for expansion-fasteners, showing my new design. Fig. 2 is a side elevation of the sleeve, taken from the opposite side of what is shown in Fig. 1.
- 15 As shown in the drawings, the leading or material feature of my design consists of a substantially-cylindrical sleeve having its central portion of less diameter than its ends and presenting the appearance when viewed
- 20 from one side of a fork having its tines of substantially-equal length and terminating in enlarged extremities.

A is a sleeve of my design. The central portion a of said sleeve is of less diameter than its end portions a' a'' , which are substantially equal in length. One side of the sleeve A is formed with a slot a^3 , as seen in Fig. 1, which extends from one end face of said sleeve to a point in proximity to its op-

posite end face and terminates in an enlargement a^4 . This slot a^3 divides the contiguous portion of the sleeve into two substantially-equal parts and gives the sleeve the appearance of a fork having its tines of substantially-equal length and terminating in enlarged extremities. The opposite side of the sleeve A is provided with a slot a^5 , extending throughout the length of the sleeve, as seen in Fig. 2.

The contour and configuration of a sleeve showing my design impart a characteristic appearance to said sleeve.

Having described my invention, what I claim as new, and desire to secure by Letters Patent, is—

The design for a sleeve for expansion-fasteners, substantially as herein shown and described.

In testimony whereof I have hereunto signed my name, in the presence of two attesting witnesses, at Syracuse, in the county of Onondaga, in the State of New York, this 8th day of January, 1898.

EDWIN J. McCORMICK.
